UNITED STATES PATENT OFFICE.

LOUIS H. FREYMUTH, OF LOS ANGELES, CALIFORNIA.

GAS-FURNACE AND CONNECTIONS FOR PARTS THEREOF.

1,135,006.

Specification of Letters Patent.

Patented Apr. 13, 1915.

Application filed September 25, 1913. Serial No. 791,747.

To all whom it may concern:

Be it known that I, LOUIS H. FREYMUTH, a citizen of the United States, residing at the city of Los Angeles, in the county of Los Angeles and State of California, have invented new and useful Improvements in Gas-Furnaces and Connections for Parts Thereof, of which the following is a specification.

In the construction of gas furnaces it is desirable to have the combustion chamber and fume conduits disconnected from the air heating chambers and the conduits which carry the heated air to its place of use. It is also desirable to so arrange the parts that the minimum quantity of heat will escape in the fume conduits. In order to produce these results in the most economical manner it is necessary to construct a portion of the furnace of cast metal and a portion thereof of sheet metal.

It is the object of my invention to accomplish the connection between the cast and sheet metal parts in such manner that the joints therebetween shall be absolutely gas tight and to do the work with the minimum amount of labor.

A further object is to so arrange the parts that the minimum amount of heat will escape in the fume conduits.

I accomplish these objects by the construction and arrangement of parts described herein and illustrated in the accompanying drawings forming a part hereof in which:—

Figure 1 is a front elevation of a three unit furnace with parts broken away. Fig. 2 is a plan view of Fig. 1 partly broken away. Fig. 3 is a front elevation of a detached unit. Fig. 4 is a view in elevation of a detached unit. Figs. 5 and 6 are sectional detail views of the different connections between the cast and sheet metal parts. Fig. 7 is a perspective of the top wall of the combustion chamber. Fig. 8 is a longitudinal horizontal section of a three unit furnace. Fig. 9 is a section on the line 9—9 of Fig. 8.

In the drawings I have illustrated my furnace as being constructed of units so that furnaces of different capacities may be principally constructed from the same kind of parts but a single unit may be provided with a cover and an outer jacket and constitute a furnace.

I will describe my furnace as formed of three units. Each unit is constructed in a similar manner and comprises a combustion

chamber 10, preferably rectangular. The sides, bottom and end walls of the combustion chamber are preferably made of sheet metal. The top wall 11 of the combustion chamber is formed of cast metal and has as many flue openings 12 therein as there are flues in the unit. I have shown six. In practice there are usually eight of these flues but there may be as many as desired.

Around each flue opening there is an upwardly extending flange 13 and around and near the outer edge of wall 11 is a downwardly extending flange 14. On flange 14 are placed sheet metal S-shaped connecting strips 15 having oppositely opening troughs. In the troughs on the other sides of the connecting strips are received the tops of the side and end walls of the combustion chamber. A suitable quantity of cement (not shown) may be used in these troughs to make the joint absolutely tight. Bolts 16 hold plate 11 connected to the bottom of the combustion chamber. Like shaped connecting strips are placed on the ledges 80 around the flue openings. The bottoms of the combustion flues 17 are received in the troughs on the other sides of the connecting strips and cement may be used in the troughs when the parts are assembled. The tops of the combustion flues are closed by cast iron plates 18 having downwardly extending flanges 19. S-shaped connecting strips 35 are used between the tops of the combustion flues and the closure plates 90 therefor. Extending across the closure plates of the combustion flues is a bar 20 which is connected by bolt 21 to the top of the combustion chamber. These bolts and bar hold the parts positively against accidental separation. Near the top and in the edge wall of each combustion flue is a small port 22 which opens into a fume chamber 23. This fume chamber extends across the edges of the combustion flues that form a 100 unit. Its height is about one-half that of the flues to which it is attached. It is narrow and the top, bottom and side walls are formed of sheet metal and the end walls 24 are of cast iron with inwardly projecting 105 flanges around the edges. These end walls are secured to the other portions by the S-shaped connecting strips and are secured together by bolts 25. In the top portion of one of the end walls is an opening 26 110 which has a circular flange 27 around it shown by dotted lines in Fig. 1 to which a

conveyer pipe 28 is attached. This conveyer pipe connects the fume chambers of all the units at the top thereof and opens into a stack 29. To the center of the bottom of each fume chamber is connected a pipe 30 which runs down to and connects with a conveyer pipe 31 which pipe runs below the combustion chambers and opens into stack 29. Pipes 30 and 31 carry off the main portion of the products of combustion. The other portion is carried off by pipe 28. A burner 32 runs longitudinally of each combustion chamber and is supplied with the usual cocks and supply pipe so that each burner can be independently regulated.

In the construction of a furnace one or more units is or are inclosed by a sheet metal cover 33 in which the units are suitably held at a distance from the side and end walls. This cover extends to the bottoms of the combustion chambers and from the top thereof the heated air is led to its place of use in the usual well known manner. An open top outer jacket 34 incloses the units and cover which are spaced therefrom an inch or two so that all the air to be heated is drawn down between the cover and jacket and then passes up between the combustion flues and other parts and is heated by the heat from such parts. The units are supported a suitable distance above the bottom of the outer jacket. It will be observed that the combustion flues and fume chambers are relatively wide and narrow thereby providing a very large radiating surface. This construction is rendered economical and practical by the use of cast iron ends for the parts which are provided with flanges. The use of cast iron ends is rendered eco-

nomical and practical by the use of my S-shaped connecting strips. These connecting strips can be used to join any cast iron part to a sheet metal part without the use of rivets.

Having described my invention what I claim is:

1. In a hot air furnace the combination of sheet metal flues; cast iron tops for said flues, said tops having downwardly projecting flanges; a combustion chamber having a cast iron top with flue openings therein and upwardly projecting flanges around said openings and having the other walls of said chamber of metal; and S-shaped sheet metal connectors, the troughs of which on one side receive the flanges of the cast iron parts and on the other side the troughs receive the ends of the flues.

2. In a gas furnace a plurality of separated combustion flues, each connected to the top of a combustion chamber and having a port in its edge wall near the top thereof; a fume chamber connected to the combustion flues by the ports near the tops thereof; a transverse bottom conveyer pipe below the combustion chamber; a connection from said conveyer pipe to the bottom of said fume chamber; a transverse top conveyer pipe connected to the fume chamber near the top; and a stack connected to said top and bottom conveyer pipes.

In witness that I claim the foregoing I have hereunto subscribed my name this 13 day of September, 1913.

LOUIS H. FREYMUTH.
